UNITED STATES PATENT OFFICE.

CHARLES J. SNYDER AND ZAVALA LEWIS, OF TOPEKA, KANSAS.

RAIL-SPlicing SAFETY-LOCK.

SPECIFICATION forming part of Letters Patent No. 308,810, dated December 2, 1884.

Application filed October 26, 1883. (Model.)

To all whom it may concern:

Be it known that we, CHARLES J. SNYDER and ZAVALA LEWIS, citizens of the United States, residing at Topeka, in the county of Shawnee and State of Kansas, have invented 5 certain new and useful Improvements in Rail-Splicing Safety-Locks, of which the following is a specification, reference being had therein to the accompanying drawings.

Our invention relates to improvements in rail-splicing safety-locks; and it consists in the novel construction and combination of the several parts, as will be hereinafter described, and pointed out in the claim.

In the drawings, Figure 1 is a side view of our improved joint. Fig. 2 is a longitudinal section on line x , Fig. 1. Fig. 3 is a detail view of the bolt; and Figs. 4, 5, 6, and 7 are detail views showing the boxing, packing, 20 and locking-plate, all of which will be described.

The rail A is provided with perforations a near its end, and fish-plates B B' are arranged on opposite sides of the rail, and provided 25 with openings b , registering with the openings a in the rail. These openings b are formed with eccentric extensions or notches b' to receive the lugs or ears on the boxing, presently described. The bolt C is provided with a 30 head, C', and on it near the said head we form the wings c , which fit the notches b' in the bolt-hole b , and prevent the bolt from turning, as will be readily understood. The boxing D is composed of base-plate d and 35 flange or rim d' . An opening, d^2 , is formed through the base-plate to permit the passage of the bolt C. Ears or lugs e are projected outward, on opposite sides of the opening a , and fit into the notches b' of opening b , and 40 keep the boxing from revolving in the operation of the device. Recesses e' are formed in the upper and lower edges of the flange d' , to receive the arms of the locking-plate, and lugs e^2 are projected forward from the 45 opposite sides of said flange, as shown. These lugs are turned down against the locking-plate and secure the same in place in the boxing in the operation of the device. The packing-ring E is preferably made of rubber, and is 50 conformed to the boxing D, in which it is placed. Its opening E registers with the

bolt-opening in the rail, fish-plates, and boxing, as readily seen in Fig. 2. The locking-plate F is preferably made of brass or other malleable metal, and is made of a shape and size equal to the interior diameter of the boxing. It has a bolt-hole, f , and arms f' are extended from its upper and lower edges, and are fitted to rest in the notches or recesses e' , formed in the boxing, as before described, 55 and the plate is placed in such boxing with its outer face flush, or approximately so, with the face of the boxing. The interior of the boxing is made in an oval or other eccentric shape, so that the locking-plate will not revolve when placed therein in the application of the device. The nut G is of ordinary construction, and in operation is turned on the outer end of the bolt down against the locking-plate, the arms of which are then turned 60 down against the faces of the nut, and the same is securely locked. The unlocking of the nut is readily accomplished by the rebending of the arms in a manner that will be apparent. 70

Where so desired, the packing-ring may be dispensed with; but we prefer its use for the following reasons:

It is found in practice that the jarring or vibration caused by the running of cars over 80 the joints in railroad-rails tends not only to loosen the nuts, but, where bolts are rigidly fitted or secured, to damage the bolts themselves, so that bolts having nuts securely locked would be much less durable, unless 85 packing be used to soften or deaden or counteract the effect of the constant vibration or jarring.

It is obvious that where so desired, instead of using the notches in the bolt-opening and 90 wings on the bolt and lugs e on the locking-plate, the boxing could be keyed on the bolt by the well-known feather and key fastening, or in various other ways. We prefer, however, the construction shown and described, 95 as thereby a firm fastening of the parts is had and a simple, easily-operated device is provided.

Having thus described our invention, what we claim, and desire to secure by Letters Patent, is—

The combination, with the bolt C, the nut

G, and the fish-plate B, having an elongated bolt-hole, of an elongated boxing, D, having the lugs e e depending from its lower end, and having the notches e' formed in the edges of its opposite sides, and the points e^2 e^2 projected upward from its ends, the elongated elastic supporting-block E, provided with a bolt-hole and fitting in the casing D, the nut-locking plate F, having elongated central portion or body, F', fitting into the casing D over the block E, and having the wings f' f' extended

outward and resting in the notches e' e' , and turned up against the nut, to permit the strain of the nut to fall upon the elastic block, substantially as set forth.

In testimony whereof we affix our signatures in presence of two witnesses.

CHARLES J. SNYDER.
ZAVALA LEWIS.
